CLAIM

The ornamental design for a medical pressure gauge pillow, substantially as shown and described.

DESCRIPTION

FIG. 1 is a bottom plan view of a medical pressure gauge pillow showing one embodiment of my new design;

FIG. 2 is a front view thereof, the rear view being substantially identical;

FIG. 3 is a top plan view thereof;

FIG. 4 is a right side elevational view thereof;

FIG. 5 is a left side elevational view thereof;
FIG. 6 is a bottom plan view of a medical pressure gauge pillow showing another embodiment of my new design;

FIG. 7 is a front view thereof, the rear view being substantially identical;

FIG. 8 is a top plan view thereof;

FIG. 9 is a left side elevational view thereof; and

FIG. 10 is a right side elevational view thereof.

FIG. 1

FIG. 2

FIG. 3

FIG. 4

FIG. 5
